UNITED STATES PATENT OFFICE.

RUDOLPH SANDERS, OF NEW YORK, N. Y.

FOLDING LOUNGE.

SPECIFICATION forming part of Letters Patent No. 712,599, dated November 4, 1902.

Application filed October 30, 1901. Serial No. 80,520. (No model.)

To all whom it may concern:

Be it known that I, RUDOLPH SANDERS, a citizen of the Kingdom of Roumania, residing at the city of New York, in the county of New York and State of New York, have invented a new and useful Improvement in Folding Lounges, of which the following is a specification, reference being had to the accompanying drawings and to the letters of reference marked thereon.

The invention relates to that class of lounges which when extended form a comfortable reclining-couch and which when folded resemble in their shape a closed writing-desk and occupy but little room.

The nature of the invention will be fully understood from the following general description and the annexed drawings and will be subsequently pointed out in the claims.

Figure 1 of the accompanying drawings, which are hereby made a part of the specification, is a side view in elevation of my newly-invented folding lounge, showing various parts of the frame and illustrating how they are hinged together. Fig. 2 is a foot end view of the same, showing a part of the frame and illustrating the construction of that part. Fig. 3 is a side view in elevation of the same when folded up, illustrating how the various parts of the frame fold together.

Similar letters of reference denote similar parts in all the figures.

In the said drawings, a , a' , a^2 , and i designate the different sections of the side rail. On either side are the parts designated by a' and a^2 . These are straight pieces of angle-iron of proper size. There are two of each, one on each side of the lounge, and they are hinged together by their ends at p , as illustrated. The parts a and i are U-shaped pieces of angle-iron, hinged by their ends, respectively, to the outer ends of the parts a' and a^2 at p' and l , as illustrated.

b and b' designate the legs of the lounge. There are four of these, which are rigidly fastened to the rail-sections a' and are strengthened by the braces v , v' , and v^2 .

The rail-section i , which, as aforesaid, is hinged to the section a^2 at l , is held in inclined position by the braces i' i^2 . The brace i' is hinged by one end to the rail-section i at l^2 and by the other end to the brace i^2 at l' .

The brace i^2 is hinged by one end, as just described, to the brace i' and by the other end to the rail-section a^2 at l^2 . These two parts i' and i^2 are so arranged that they form a flexible support for the rail-section i . This section i is a headpiece of the lounge. The horizontal braces h' are rigidly fastened to the legs b and b' . There are two of these, one fastened to each pair of legs on either side of the lounge. To these braces h' are hinged the brace-straps h and h^2 at k' and k^2 , respectively.

To support the foot-section a of the lounge, the U-shaped brace d is provided. This is hinged by its ends to the foot-section a of the side rail at p^2 and to the brace-straps h at k . The head end of the lounge is supported by the brace d' . This is hinged by its upper ends to the rail-section a^2 and to the brace-straps h^2 at k^2 . Additional brace-straps d^2 are hinged to the rail-section a^2 at q and to the horizontal brace h' at k^2 for the support of the structure. The bottoms of the legs b and b' are provided with casters n and n' . The whole device is to be substantially as illustrated in the drawings.

When the lounge is in the position illustrated in Fig. 1, it will be found to be a very comfortable reclining-couch, and on account of the fact that the head-section i is always held in inclined position it may be made a little longer than an ordinary straight lounge and not at the same time occupy any more floor-room.

When the lounge is folded up into the position illustrated in Fig. 3, the shape of the lounge very nearly resembles that of a folded writing-desk. This is effected by raising the outer ends of the rail-sections a and a^2 so that these two sections will assume a perpendicular position. Then the outer end of the head-section i will fold up against the outer end of the section a and all the accompanying mechanism will automatically assume the positions illustrated in Fig. 3. It will then be found that the lounge, while it presents a very slight appearance, occupies a minimum of floor-room and as it is mounted on casters may be wheeled about to any desired position in the room where it is used.

Having now described what my invention is and in what way the same is constructed

and used, what I claim as my invention, and desire to secure by Letters Patent, is—

In a device of the type set forth, the combination with the side rails, comprising a series of hinged sections, the end sections of which are U-shaped and pivotally connected to the inner sections of the said side rails, of a U-shaped brace hinged to one of the said end sections, means for limiting the movement of the other end section, legs rigidly secured to the inner of the side rail's sections, horizontal braces rigidly secured to the said legs, brace-straps pivotally secured to the said U-shaped brace and to one end of the said

horizontal braces, vertically-arranged braces 15 hinged to one of the inner rail-sections, and brace-straps hinged to the last-named braces and to the adjacent ends of the said horizontal braces, substantially as described.

In testimony whereof I, RUDOLPH SANDERS, have signed my name to this specification, in the presence of two subscribing witnesses, this 23d day of October, 1901.

RUDOLPH SANDERS.
